(57) **CLAIM**

The ornamental design for a table, as shown and described.

DESCRIPTION

FIG. 1 is a front elevational view of a table showing my new design;

FIG. 2 is a right side elevational view thereof, the opposite side view being a mirror image;

FIG. 3 is a top plan view thereof;

FIG. 4 is a rear elevational view thereof;

FIG. 5 is a bottom plan view thereof;

FIG. 6 is a cross-sectional view taken along the lines 6—6 in FIG. 1;

FIG. 7 is a perspective view of the table; and,

FIG. 8 is an enlarged perspective view of a fragment of the table as shown in FIG. 7.

The broken lines are for environmental purposes only and form no part of the claimed design.

1 Claim, 8 Drawing Sheets
